COMBINED SOUND REPRODUCING-
RECORDING APPARATUS

Paul Stead Gay, Charlotte, Mich., assignor to
Wilcox-Gay Corporation, Charlotte, Mich., a
corporation of Michigan

Application March 3, 1941, Serial No. 381,555

10 Claims.

(Cl. 274—13)

My invention relates to sound recording and reproducing apparatus and more particularly to a combination recorded and reproducer using a single operating arm; and is a continuation-in-part of my application Serial No. 320,823, filed Feb. 4, 1940.

In my aforementioned application, there is shown a combination unit having a single turn-table and driving means and separate recording and play-back (or reproducing) arms, each having a novel construction and previously unknown means of integration with the remainder of the apparatus.

An important object of the present invention, and the major distinction thereof over my prior application and over other prior apparatus is the provision of a single arm which is capable of performing both the cutting (recording) and play-back (reproducing) functions.

A corollary object, therefore, is the provision in sound apparatus having a single operating arm of a translating means which will serve to transmit sound impulses or vibrations to the recording or cutting needle and which will also serve to receive sound impulses or vibrations from a reproducing or play back needle, and translate them for aural reproduction.

A further object of the present invention is the provision in connection with a unitary sound recording and reproducing arm of means for readily selectively positioning the arm to perform either the recording or reproducing function and for maintaining the arm in selected position.

Still a further object is the provision of drive means for the arm when the same is performing its recording function, while at the same time providing means for automatically disengaging the driving means when the arm is positioned and operated to perform the reproducing function.

These and many other objects of my present invention will in part be apparent and where not apparent, pointed out, in the following description and drawings, in which:

Figure 1 is a view in perspective, partially broken away, showing the novel apparatus of my present invention;

Figure 2 is a view partly in cross-section, taken along the line 2—2 of Figure 1 looking in the direction of the arrows;

Figure 3 is an elevation, partly in cross-section, taken along line 3—3 of Figure 1, looking in the direction of the arrows and showing the apparatus arrangement for sound reproduction (play-back);

Figure 4 is a view corresponding to that of Figure 3 showing the apparatus arranged for sound recording (record cutting);

Figure 5 is a cross-sectional view showing the mounting of the operating arm and taken along

line 5—5 of Figure 3, looking in the direction of the arrows.

Referring now to the figures, I have here shown sound recording and reproducing apparatus, having the novel form of my invention, and mounted on a base 10, which may be supported in any suitable manner in the top of a cabinet (not shown).

The base 10 has an enlarged opening therein 10 over which is mounted the motor mounting plate 11 (see particularly Figure 1) which plate is secured to the base by the screws 12 or in any other suitable manner.

A motor 13 (see Figures 3 and 4) is suspended 15 from the under side of the plate 12 by means of bolts which pass through the mounting plate 12 and are secured by nuts 15. Resilient rubber grommets 16 are provided between the nuts 15 and the plate 12 in order to provide a resilient 20 mounting for the motor so that the field poles thereof may rotate to compensate for power pulses and thus prevent the creation of hum in the record. This particular mounting of the motor and the function and operation of the 25 resilient grommets are fully described in my application above mentioned; and while this mounting forms a valuable and useful part of the present apparatus, it constitutes no part of the present invention. The apparatus of the present invention may be utilized in connection with any appropriate power source and any suitable type of 30 mounting therefor.

The motor shaft 20 extends upwardly vertically 35 through an opening in the mounting plate 12 and hence projects on the upper side of base 10.

The motor shaft 20 is in surface to surface engagement with the periphery of a rubber tired idler 22 which in turn is engaged with the inner surface of a dependent flange 23 of the turn-table 24. The turn-table rotates on the spindle 25 and causes the same to rotate for the purposes hereinafter set forth.

The rubber surfaced idler 22 is compressed between the flange 23 and the motor shaft 20 and 45 thus furnishes a resilient driving connection therebetween which further serves to reduce the effect of power pulses and other motor noises in the manner described more fully in my application above mentioned.

50 Compression of the rubber peripheral surface of the idler, however, does not affect the speed ratio of power transmission since changes of the diameter of the idler have no effect. This is so because whatever linear movement is transmitted 55 to the surface of the idler by the motor is transmitted in equal degree to the surface of the turn-table flange irrespective of changes in diameter of the idler.

The shaft 28 on which the idler 22 rotates is 60 rotatably mounted on a mounting plate 30. The

mounting plate 30 has an annular boss 31 which bears against the base plate 11. A bolt 32 secured to the mounting plate passes through an enlarged opening 33 in the base plate 11 and carries secured thereto and positioned thereon by the nut 34 the washer 35, the said washer also having an annular boss 36 which bears against the under side of the plate 11.

The pressure of the washer 35 against the under side of the plate 11 thus serves to secure the mounting plate 30 on the plate 11. The hole 33 in the mounting plate 11 through which the bolt passes has a larger diameter than the bolt 32, and accordingly the mounting plate 30 is permitted some movement with respect to the plate 11. The plate 30 is resiliently biased outwardly and away from the motor shaft 20 by the tension spring 40, one end of which is at 41 attached to the bolt 32 and the other end of which is at 42 hooked through a perforation 43 in the plate 11.

The placement of the turn-table 24 upon the spindle causes the flange 23 thereof to move the idler 22 against the bias of the spring 40 into engagement with the shaft 20. In the event that when the turn-table is mounted on its spindle, the distance from the flange to the shaft 20 is less than the diameter of the idler 22, then, by reason of the fact that the hole 33 is much larger than the bolt 32, the bolt 32 may be moved along an arcuate path (with the distance between the shaft 20 to the bolt 32 as a radius) until the idler has been adjusted so that both the shaft 20 and the flange 23 are in abutment therewith.

Thus the shaft 20 and the point of contact of the idler 22 with the flange 23 are not diametrically opposite each other across the idler, but rather are in the relationship shown in Figure 2 when the turn-table is placed on the spindle. By this means, also, the rubber tire on the idler 22 is compressed between the flange 23 and the motor shaft 20 to ensure the transmission of power therethrough.

The basic elements of the operation of the idler and of the mounting therefor above described have been set forth in my application Serial No. 320,823, and I have here set forth in detail only the variation in the mounting which falls, however, within the basic principles of the idler mounting therein described.

The foregoing apparatus has been set forth in detail in order to describe more particularly the environment and structure with which my present invention is intended to cooperate. The contribution of the present invention relates specifically to the combination pick-up and recording arm 50 which may be selectively positioned in order to perform the function of playing back a record which has already been cut or of cutting a blank record in accordance with the modulations impressed on the element carried by the arm.

As is seen in Figures 1, 3 and 4, the pick-up arm 50 carries at the forward end thereof a cartridge 51 which may function both as a pick-up head or a cutting head. In the preferred form, the cartridge 51 contains a piezo-electric crystal the functions and operations of which for recording and play back purposes are well known in the art.

The piezo electric crystal in the cartridge 51 is by the circuit connection 52 connected to any suitable circuit which may operate to translate modulations impressed on the crystal into sound or it may be adjusted to impress modulations upon the crystal in order to translate sounds into

vibrations of a stylus carried by the cartridge 51.

The circuit connection 52 is so arranged in connection with switches (not shown) that it may be selectively connected to apparatus for translating modulations into sound or for translating sound into modulations of the crystal in the cartridge head. Such circuit connections, switches and apparatus may, if desired, constitute a simple adaptation of the elements shown in my application Serial No. 377,307 filed February 4, 1941.

The position shown in Figures 1 and 3 of the combination pick-up and recording arm 50 is that for pick-up or play back of records which have been cut. The position shown in Figure 4 is that for cutting a record in accordance with sounds which are impressed on the crystal in the cartridge 51.

The change in position from the Figure 4 position to the Figure 3 position (and vice versa) must be accompanied by a corresponding switching operation to connect the cartridge 51 to the appropriate circuits for either recording or playing back. Such switching operations may be automatically performed by the change in position of the arm 50 or may be separately performed by a suitable switching dial, knob or lever having a plurality of switching positions.

The combination pick-up and recording arm 50 is as is seen more particularly in Figure 5, pivotally mounted at 60 and 61 on the plate 62. The plate 62 has vertical flanges 63 and 64 which have small perforations 65 and 66 therein in which the conical points 67 and 68 of the screws 69 and 70 may be mounted.

Nuts 71 and 72 mounted on the screws 69 and 70 may serve to position them appropriately with respect to the arm 50 and the flanges 62 and 63. By this means, therefore, a simplified needle bearing for the arm 50 upon the plate 62 is provided. This double needle bearing for the pivot of the arm 50 permits the arm to be swung readily in a vertical plane in order to position the same properly with respect to a record while rotation of the arm necessarily results in rotation of the plate 62 since with respect to rotation in a horizontal plane, the needle bearing is a playless one.

The plate 62 is secured to the top of a post 80 in such manner that it is integrated therewith and so that rotation of the post will result in rotation of the plate and vice versa.

The post 80 is rotatably mounted in the journal 81 which in turn is secured in any suitable manner in the top 10 of the cabinet which contains the entire apparatus. The lower end of the post 80 carries secured thereto and rotatable therewith a feed arm 90 so that any movement of the feed arm will result in corresponding rotation of the post 80. The feed arm 90 serves the function of rotating the post 80 and consequently rotating the combination recording and pick-up arm in a horizontal plane so that the cutting needle or stylus 100 may be driven slowly inwardly towards the spindle 25 of the turn-table, thus cutting a spiral groove in the record disk 101 as the turn-table 24 rotates.

It is necessary, however, that the feed arm 90 be disconnected from any driving force when it is desired to use the combination play back or cutting arm for playing back a record which has been cut. The vertical slideability of the post 80 in its journal 81 serves to accomplish this function.

When the apparatus is in the positions shown in Figures 1, 3 and 5, with the post 80 moved down to its lowest position, and with the combination pick-up and recording arm 50 virtually parallel

to the surface of the record, then the apparatus is set for the play back position and the grooves in the record which has already been cut may be translated into sound.

For this purpose then, in the lowered position shown in Figures 1, 3 and 5, the feed arm 90 is disconnected from the driving screw 110 and the combination pick-up and recording arm 50 is free to rotate with its post and with the feed arm in order to follow the grooves in the record. That is, although the feed arm and the post rotate as the arm 50 rotates, when the record is being played back, they perform no operative function at that time.

When, however, the post 80 is slid upwardly to the position shown in Figure 4, then the feed arm 90 is likewise moved upwardly and the pawl 120 on the end thereof is engaged with the threads of the screw 110. The pawl 120 as may readily be seen in the figure, is preferably a flat strip of spring metal which is secured by the rivets 130, 130 to the end of the feed arm 90 and which is bent up at 131 and 132 to provide the pawl or knife edge 120.

The angle of the bend 131 is preferably an obtuse angle and is as close to 180° as possible in order that the spring metal of the pawl 120 should be permitted to have substantially no lateral compliance. The reason for the bend at 131, however, is to provide a certain amount of vertical compliance or resilience in order to ensure that the knife edge 120 will be forced into the threads of the screw 110 so that a driving engagement may exist between the screw 110 and the feed arm 90. The screw 110 is rotated when the turn-table 24 rotates by a suitable gear connection 140 between the said screw 110 and the spindle 25 which rotates with the turn-table.

It will now be clear that when the post 80 is slid upwardly to the position shown in Figure 4 and the knife edge pawl 120 of the feed arm 90 is engaged with the threads 110 of the screw, that rotation of the turn-table 24 causing rotation of the spindle 25 will through the gear connection 140 cause rotation of the screw 110 and consequently cause the pawl 120 to move along the screw, thus rotating the feed arm 90, rotating the post 80 and rotating the combination recording and pick-up arm 50 slowly towards the spindle so that a spiral groove may be cut in the record disk 101 on the turn-table.

A suitable stop 150 may be provided to prevent movement of the feed arm to such a position that the stylus 100 on the combination pick-up and recording arm 50 may not move too close to the spindle.

When the combination arm 50 is in the position shown in Figure 3, then the plate 62 resting on the top of the journal 81 provides an appropriate stop for the post 80 so that the post is accurately positioned within the journal 81 and so that the combination arm 50 is properly positioned for playing back a record. In this case, an ordinary play back needle 200 may be inserted in the cartridge 51 and secured therein by the screw 201. It is necessary, however, to likewise provide a support for the post 80 when it is in its raised position and when the feed arm 90 is in operative engagement with the screw 110.

For this purpose, I have provided a dependent flange 210 beneath the top 10 of the cabinet and I have secured a flat spring 211 thereto by the rivet 215. The flat spring 211 is bent so as to provide a chamfered surface 212 on the under side 75

thereof, and a supporting and chamfered surface 213 on the upper side thereof.

The extending lug 214 which is secured to the post 80 (and which is also part of the feed arm 50 for purposes hereinafter described), is so arranged that when the post 80 is slid upwardly in its journal, the plug 214 will first engage the chamfered surface 212 of the spring 211 and move the same towards the left with respect to Figures 10 3 and 4.

After the lug 214 has passed the peak of the chamfered surface 212, it will then be engaged with the surface 213 in the manner shown in Figure 4, and will thus rest thereon. The spring 15 211 is sufficiently strong to maintain its position shown in Figure 4 wherein the surface 213 thereof supports the weight of the post 80, the combination arm 50 and the feed arm 90, and accordingly will support the apparatus in operative 20 position for recording purposes.

When it is desired to disengage the combination arm 50 from its recording relationship and to play it once more in play back relationship, simple manual pressure in the area 220 of the 25 combination arm 50 will serve to force the post 80 downwardly and press the lug 214 down on the surface 213 to cause the spring 211 once more to move to the left and thus disengage the lug 214 from its support by the spring and thus permit the apparatus to return once more to the 30 position shown in Figure 3.

When it is desired to raise the apparatus to recording position once more, then simply grasping the combination arm 50 at the rear end 35 thereof adjacent the screws 69 and 70, and lifting the same will cause the lug 214 to pass the chamfered surface 212 and come to rest on the surface 213 where the apparatus is once more in recording position.

40 A cutting stylus 100 then inserted in the cartridge 51 and held therein by the screw 201 will now serve to translate sound modulations impressed on the piezo electric crystal of the cartridge 51 into sinusoidal grooves in the surface of the record.

45 The lug 214 may, of course, be attached to the post in any suitable manner. Also, the edge thereof which is in engagement with the spring should be appropriately curved so as not to impede free rotation of the post when the post is in the position shown in Figure 4.

In the present embodiment, I have shown the lug 214 as part of the feed arm which in turn is secured to the post 80 by means of the set screw 240 which passes through the vertical flange 241 and is engaged against the milled surface 242 of the end of the post 80. The milled end 242 of the post 80 thus passes through perforations in the lug 214 and in the main portion of the feed arm 90 and the engagement of the screw 240 serves to position the same accurately and positively with respect to the post.

60 In the event that it is desired to adjust the feed arm in order to adjust the position of the pawl 120 with respect to screw 110, then a simple loosening of the set screw 240 will permit the said arm to be slid upwardly or downwardly on the milled end 242 of the post in order to adjust the horizontal position of the feed arm 90 and in order to provide for the appropriate adjustment of the pawl 120 with respect to the screw 110.

65 For play back purposes, it is usually desirable that the play back needle 200 occupy the angular position shown in Figure 3 with respect to the record disk in order that the needle 200 may trail

appropriately in the grooves. Accordingly, the opening in the cartridge 51 in which the needle 200 is to be mounted, is properly slanted in order to provide this relationship.

However, for cutting a record, it is necessary that the cutting edge should not trail with respect to the record but should be substantially normal thereto. The raising of the end 229 of the combination arm 50 to the position shown in Figure 4 thus causes the combination arm 50 to slope 10 downwardly towards the front thereof in the manner shown in Figure 4, thus making the slanted opening of the cartridge in which the needle is mounted more nearly vertical, thus permitting the cutting stylus 100 to assume the 15 proper vertical cutting position which is necessary for cutting a record.

Thus the movement of the arm 50 to the position shown in Figure 4 normally serves to engage the feed arm in driving relationship but also 20 serves to change the position of the cartridge so that the cutting stylus when placed therein will have the proper relationship to the record surface in order to ensure proper cutting.

In the process of cutting a record, best results are obtained when stylus pressure is properly maintained, that is, when the pressure of the cutting stylus is neither too heavy nor too light. The weight of the combination arm 50 is preferably 25 such as to ensure appropriate cutting pressure. But in order to ensure that some adjustment may be made, the cutting arm may be made so that the weight thereof on the cutting stylus will be slightly greater than is necessary for proper cutting pressure.

The weight of the arm itself, however, may then be counteracted somewhat by the leaf spring 250 which is secured in any appropriate manner such as by rivets 251 to the plate 62. The bearing surface 253 of the leaf spring 250 40 may then be so arranged that it will not cooperate in any manner with the combination arm 50 when the arm is in the position shown in Figure 3.

When the arm is raised and sloped in the manner shown in Figure 4, then the bearing surface 253 of the leaf spring 250 may be brought into supporting relationship with the under surface of the arm 50 and serve partially to support the same. Adjustment of the leaf spring 250 by 45 manually bending the same so that it provides more or less supporting pressure for the arm 50 will serve therefore to adjust the pressure on the cutting stylus 100.

When the apparatus is not in use, the combination arm 50 may be supported on the post 300 as shown in Figure 1 in order to maintain the needle or stylus carried thereby out of engagement with any surface which may have a deleterious effect thereon. Further, a plurality of vertical tubes 301, 301, closed at the bottom end, may be provided in the top surface 10 of the cabinet in order to provide a means for retaining needles which are not in use.

This is useful with respect to the present device since needles 200 and 100 must be interchanged with each other when the apparatus is changed from play back to recording, and vice versa.

The foregoing simplified compact construction permits of the manufacture of a small unit which may be portable if desired, and which may nevertheless combine the functions of a phonograph, a recording instrument and even of a radio. In actual construction, the combined unit having

the apparatus above described in the top thereof and having amplifying equipment and the necessary sound translating equipment (both loud speaker and microphone), and radio circuits as well, may be embodied in a portable casing, the total weight of which is less than eighteen pounds.

In the foregoing, I have described the simplest and preferred embodiments of each of the aspects of my invention. Each of the elements thereof, it is now clear, may take many other forms within the spirit of this invention. I prefer, accordingly, to be bound, not by the specific disclosures herein, but only by the appended claims.

I claim:

1. In sound recording and reproducing apparatus, a turn-table and means for driving the same; an operating arm carrying a sound translating element at one end and secured at the other end on a vertical post, said post being rotatable in a journal; said post carrying a feed arm, driving means for said feed arm; means for pivotally supporting said post in said journal in one position with the feed arm disengaged from its driving means; said post being slidable to another position in said journal and means for pivotally supporting said post in said other position for engaging said feed arm with its driving means.

2. In sound recording and reproducing apparatus, a turn-table and means for driving the same; an operating arm carrying a sound translating element at one end and secured at the other end on a vertical post, said post being rotatable in a journal; said post carrying a feed arm, driving means for said feed arm; means for pivotally supporting said post in said journal in one position with the feed arm disengaged from its driving means; said post being slidable vertically in its journal to another position to engage said feed arm with its driving means, and a yielding chamfered surface for supporting said post in said raised position, said post being disengageable from said support by manual pressure on the top of said post.

3. In sound recording and reproducing apparatus, a turn-table and means for driving the same; an operating arm carrying a sound translating element at one end and secured at the other end on a vertical post, said post being rotatable in a journal; said post carrying a feed arm, driving means for said feed arm; means for pivotally supporting said post in said journal in one position with the feed arm disengaged from its driving means; said post being slidable in its journal to a raised position to engage said feed arm with its driving means; a lug at the bottom end of said post, a yielding chamfered surface for engaging said lug and supporting said post in raised position, said lug being disengageable from said supporting surface by manual pressure on the top of said post.

4. In sound recording and reproducing apparatus, a turn-table and means for driving the same; an operating arm carrying a sound translating element at one end and secured at the other end on a vertical post, said post being rotatable in a journal; said post carrying a feed arm, driving means for said feed arm; means for pivotally supporting said post in said journal in one position with the feed arm disengaged from its driving means; said post being slidable to a raised position in its journal to engage said feed arm with its driving means, and a yielding chamfered surface for supporting said post in said raised position, said post being disengageable from said

support by manual pressure on the top of said post, said operating arm being pivotal in a vertical plane on said post; said sound translating element being in engagement with a record disc on the surface of said turn-table in each position of said post.

5. In sound recording and reproducing apparatus, a turn-table and means for driving the same; an operating arm carrying a sound translating element at one end and secured at the other end on a vertical post, said post being rotatable in a journal; said post carrying a feed arm, driving means for said feed arm; means for pivotally supporting said post in said journal in one position with the feed arm disengaged from its driving means; said post being slidable to another raised position in its journal to engage said feed arm with its driving means, and a yielding chamfered surface for supporting said post in said raised position, said post being disengageable from said support by manual pressure on the top of said post, said operating arm being pivotal in a vertical plane on said post; said sound translating element being in engagement with a record disc on the surface of said turn-table in each position of said post, an opening in the bottom of said sound translating element for supporting a needle; the axis of said opening forming an acute angle with the surface of said turn-table in the lower position of the post; the axis of said opening being substantially normal to the turn-table in the raised position of the post.

6. In sound recording and reproducing apparatus, a turn-table and means for driving the same; an operating arm carrying a sound translating element at one end and secured at the other end on a vertical post, said post being rotatable in a journal; said post carrying a feed arm, driving means for said feed arm; means for pivotally supporting said post in said journal in one position with the feed arm disengaged from its driving means; said post being slidable to another raised position in its journal to engage said feed arm with its driving means, and a yielding chamfered surface for supporting said post in said raised position, said post being disengageable from said support by manual pressure on the top of said post, said operating arm being pivotal in a vertical plane on said post; said sound translating element being in engagement with a record disc on the surface of said turn-table in each position of said post; and adjustable yielding means carried by said post and engageable with the under side of said operating arm when the post is in raised position for partially supporting said arm.

7. In sound recording and reproducing apparatus, a turn-table and means for driving the same; an operating arm carrying a sound translating element at one end and secured at the other end on a vertical post, said post being rotatable in a journal; said post carrying a feed arm, driving means for said feed arm; means for pivotally supporting said post in said journal in one position with the feed arm disengaged from its driving means; said post being slidable to another position in said journal and for pivotally supporting said post in said other position for engaging said feed arm with its driving means; said driving means for said feed arm comprising a horizontal screw rotatable in ratio with the rotation of the turn-table, said feed arm carry-

ing a knife-edge pawl movable vertically with said feed arm into engagement with the thread of said screw.

8. In sound recording and reproducing apparatus, a turn-table and means for driving the same; an operating arm carrying a sound translating element at one end and secured at the other end on a vertical post, said post being rotatable in a journal; said post carrying a feed arm, driving means for said feed arm; means for pivotally supporting said post in said journal in one position with the feed arm disengaged from its driving means; said post being slidable to another position in said journal and for pivotally supporting said post in said other position for engaging said feed arm with its driving means; said driving means for said feed arm comprising a horizontal screw rotatable in synchronism with the rotation of the turn-table, said feed arm carrying a knife-edge pawl movable vertically with said feed arm into engagement with the thread of said screw, said knife edge pawl being resiliently mounted to have vertical compliance and little lateral compliance.

25 9. In sound recording and reproducing apparatus, a turn-table and means for driving the same; an operating arm carrying a sound translating element at one end and secured at the other end on a vertical post, said post being rotatable in a journal; said post carrying a feed arm, driving means for said feed arm; means for pivotally supporting said post in said journal in one position with the feed arm disengaged from its driving means; said post being slidable to another position in said journal and for pivotally supporting said post in said other position for engaging said feed arm with its driving means; said driving means for said feed arm comprising a horizontal screw rotatable in synchronism with the rotation of the turn-table, said feed arm carrying a knife-edge pawl movable vertically with said feed arm into engagement with the thread of said screw, said knife-edge pawl comprising a resilient substantially horizontal sheet metal member secured to the end of said feed arm and extending from one side of said arm, said knife edge pawl constituting a substantially vertical extension of said sheet metal member parallel to the axis of said feed arm.

50 10. In sound recording and reproducing apparatus, a turn-table and means for driving the same; an operating arm carrying a sound translating element at one end and secured at the other end on a vertical post, said post being rotatable in a journal; said post carrying a feed arm, driving means for said feed arm; means for pivotally supporting said post in said journal in one position with the feed arm disengaged from its driving means; said post being slidable to another position in said journal and for pivotally supporting said post in said other position for engaging said feed arm with its driving means; said driving means for said feed arm comprising a horizontal screw rotatable in synchronism with the rotation of the turn-table, said feed arm carrying a knife-edge pawl movable vertically with said feed arm into engagement with the thread of said screw; said feed arm being adjustable on said post to adjust the engagement of said pawl and said screw.

PAUL STEAD GAY.
